UNITED STATES PATENT OFFICE.

MORRIS KORNBLOM, OF BROOKLYN, NEW YORK.

DESIGN FOR A COMBINED LAMP BASE AND ASH RECEIVER.

Application filed January 25, 1926. Serial No. 16,248. Term of patent 3½ years.

To all whom it may concern:

Be it known that I, MORRIS KORNBLOM, a citizen of the United States, and doing business at 8720 Sixteenth Av., Brooklyn, New York, have invented a new, original, and ornamental Design for a Combined Lamp Base and Ash Receiver, of which the following is a specification, reference being had to the accompanying drawing, forming part thereof.

Fig. 1 is a side view of the article, showing my new design.

Fig. 2 is a front view.

I claim:

The ornamental design for a combined lamp base and ash receiver, as shown.

MORRIS KORNBLOM.
